UNITED STATES PATENT OFFICE.

HERMAN V. COOKINGHAM, OF RENSSELAER, AND GEORGE O. PRICE, OF ALBANY,
NEW YORK.

CAR-DOOR-SEALING DEVICE.

1,120,447.

Specification of Letters Patent.

Patented Dec. 8, 1914.

Application filed April 15, 1914. Serial No. 831,963.

To all whom it may concern:

Be it known that we, HERMAN V. COOKINGHAM and GEORGE O. PRICE, both citizens of the United States, and residents, respectively, of Rensselaer, in the county of Rensselaer, and State of New York, and of Albany, in the county of Albany and State of New York, have invented a new and Improved Car-Door-Sealing Device, of which the following is a full, clear, and exact description.

The invention relates to sliding door locks, such as shown and described in the Letters Patent of the United States, No. 1,042,326, granted to us on October 22, 1912.

The object of the present invention is to provide a new and improved sealing device for the locks of sliding doors of freight cars of the box or furniture type, and arranged to permit of readily locking the operating lever of the lock in place at the time the door is unlocked or locked, and to allow of sealing the door lock when the latter is in locked position to prevent tampering of the door by unauthorized persons.

In order to accomplish the desired result use is made of a lock-controlling lever fulcrumed on the car door and having an opening for engagement with one of a series of studs held on a keeper fixed to the car door, and a movable locking member on the said lever for locking the latter in position on the keeper when the lock is in open or closed position.

A practical embodiment of the invention is represented in the accompanying drawings forming a part of this specification, in which similar characters of reference indicate corresponding parts in all the views.

Figure 1 is a side elevation of a portion of a car body having a sliding door provided with the lock and sealing device; Fig. 2 is an enlarged side elevation of part of the same; Fig. 3 is an enlarged transverse section of the same on the line 3-3 of Fig. 2; Fig. 4 is a sectional side elevation of the same on the line 4-4 of Fig. 3 and showing the locking member in locking position; and Fig. 5 is a sectional plan view of the same on the line 5-5 of Fig. 4.

The door A for closing and opening in the side of the car body B is provided at its lower end with hangers C in which are journaled wheels D mounted to travel on a track E attached to the car body B, and the said

wheels D and the track E are adapted to be engaged by shoes F connected by links G with an operating lever H fulcrumed at H' on the car door A, as more fully explained in the previous patent above referred to, so that further description of this locking device for the car door A is not deemed necessary.

The operating lever H is provided near its upper end with a handle H² adapted to be taken hold of by the operator for imparting a swinging motion to the said lever H with a view to engage or disengage the shoes F from between the wheels D and the track E whenever it is desired to lock or unlock the door A. The upper portion of the operating lever H is provided with an opening H³ adapted to engage any one of a series of studs I, I', I² and I³, cast on or secured to a segmental keeper J, bolted or otherwise fastened to the car door A. The stud I is disposed vertically above the fulcrum H' of the lever H so that when the lever H engages the stud I the shoes F are held in retracted position. The other studs I', I² and I³ are arranged to one side of the stud I, and when any one of them is engaged by the lever H the latter is in locking position, as will be readily understood by reference to dotted lines in Fig. 1. Only one of the studs I', I² or I³ is engaged at a time by the lever H and a number of such studs are provided to compensate for any wear on the shoes F so as to allow giving more or less throw to the lever H before locking the same in place on the corresponding stud I', I² or I³.

Each stud I, I', I² and I³ is provided with a reduced shank I⁴, as plainly indicated in Figs. 3 and 5, and each stud I is adapted to be engaged by a movable locking member K in the form of a plate having a slot K' for engagement with the reduced shank I⁴, the slot having an enlarged portion K² near its lower end for the passage of the head of the stud to move the reduced shank I⁴ into register with the slot K'. The locking member K is mounted to slide up and down on pins or screws L passing through the slot K' and engaging the lever H, as plainly shown in Figs. 3 and 4. The lower end of the locking member K is provided with a forwardly and upwardly extending handle K² arranged in the rear of the handle H² and adapted to be taken hold of by the op-

erator for moving the locking member K upward or downward as the case may be. When the plate K is moved into uppermost position, as shown in Fig. 3, then the 5 enlarged portion K² of the slot K' registers with the opening H³ so that the lever H and the locking member K can be engaged with any one of the studs I, I', I² or I³, and when the said parts are so engaged the locking member K can be swung downward so that the slot K' engages the reduced shank I⁴ and thus locks the lever H in place to prevent the disengagement of the lever H from the corresponding stud I, I', I² or I³. The lowermost screw or pin L limits the upward movement of the locking member K, as indicated in Fig. 3, and the downward movement of the member K is limited by the bottom of the handle K³ resting on the bottom of the handle H², as indicated in Fig. 4. The bottoms of the handles K³, H² are provided with apertures K⁴, H⁴ adapted to register with each other at the time the locking member K is in lowermost position, and the said registering apertures K⁴ and H⁴ are adapted to receive a padlock, lead seal or like device N, as indicated in Fig. 4. From the foregoing it will be seen that by the arrangement described the lever H is locked 30 in place when in engagement with either of the studs I, I', I² or I³, and the locking member K is locked in place by the sealing device N to prevent tampering with the car door lock by unauthorized persons.

It is understood that in order to lift the member K into unlocking position, it is necessary to open or destroy the sealing device N, consequently the proper officials of the road can quickly detect whether a car door 40 lock has been tampered with or not.

It is understood that the operating lever H is loosely mounted at H' to allow sufficient transverse movement of the lever H to move the latter into or out of engagement 45 with the stud I, I', I² or I³.

Having thus described our invention, we claim as new and desire to secure by Letters Patent:

1. In a car door lock, the combination of

Copies of this patent may be obtained for five cents each, by addressing the "Commissioner of Patents, Washington, D. C."

the lock-operating lever fulcrumed on the 50 car door, a keeper attached to the door, the said lever having an opening and the keeper having a series of studs to hold the lever in an adjusted position, a movable locking member adapted to coöperate with said 55 studs for locking the lever in position on the keeper, and a seal engaging the said locking member to hold the latter in locking position.

2. In a car door lock, the combination 60 with the lock-operating lever fulcrumed on the door and having an opening, a keeper attached to the door and provided with a series of studs adapted to be engaged by the said lever opening, and a slotted locking 65 plate slideable on the said lever and adapted to engage the stud in engagement at the time with the lever to hold the latter in locked position.

3. In a car door lock, the combination 70 with a lock-operating lever having an opening and a handle, a fixed keeper provided with a series of studs having heads and reduced shanks, the studs being adapted to be engaged one at a time by the said lever 75 opening, a locking plate slidably mounted on the said lever under the said handle, the said locking plate having a slot for engagement with the reduced shank of a stud, the side walls of the slot having near their 80 lower ends enlarged portions for the passage of the head of a stud, the said locking plate having an angular hand-hold for sliding the locking plate into or out of locking position, the said hand-hold being 85 adapted to engage one end of the handle, and the said hand-hold and the said handle having openings adapted to register with each other for the reception of a seal.

In testimony whereof we have signed our 90 names to this specification in the presence of two subscribing witnesses.

HERMAN V. COOKINGHAM.
GEORGE O. PRICE.
